REAMING COLLAR FOR DRILL STEELS

John Alger, Lakewood, Colo.

Application May 2, 1949, Serial No. 90,926

5 Claims. (Cl. 255—61)

1 This invention relates to an attachment for rock drilling steels. When drilling relatively deep, vertical holes, the air exhaust from the bit of the drill steel is unable to raise the rock dust to the top of the hole. This dust therefore accumulates in a packed dust ring about the drill steel above the bit. When the drill steel is drawn upwardly for removal from the hole, the enlarged bit extremity becomes wedged into this dust ring with sufficient force to prevent rotation of the drill steel and withdrawal of the latter.

The principal object of this invention is to provide a simple, easily applied attachment for a drill steel which will act to quickly remove this dust ring as the steel is withdrawn from the hole so as to prevent loss of the steel.

Another object of the invention is to so construct the attachment that no changes of any kind need be made in the conventional drill steel or bit, and to provide an attachment for this purpose which can be applied to the drill steel either before or after its insertion in the drill hole.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the bit extremity of a conventional drill steel, illustrating it in place in a drill hole with the improved attachment in place thereon;

Fig. 2 is a plan view of the improved dust ring removing attachment; and

Fig. 3 is a cross-section through an alternate form of the attachment, taken on the line 3—3, Fig. 4;

Fig. 4 is a side view of the alternate form of Fig. 3.

In Fig. 1 a conventional, hexagonal drill steel is illustrated at 10, with its bottom bell 11 and with a conventional drill bit applied thereto, as indicated at 12.

In Fig. 1 the steel and bit are in place in a drill hole 13 in which a dust ring 14 has been built up by the air discharge through the bit 12. This dust ring is the result of the powdered dust, created by the drilling action, being blown up-

wardly by the air exhaust through the drill steel and bit.

The improved attachment comprises two relatively thin, metallic, half shells 15 and 16 secured together by means of removable pins 17 passing through interlocking pin sleeves 18 which are formed on the adjacent edges of the shell 16. A plurality of cutting blades 19 are welded or otherwise secured to the upper extremities of the shells 15 and 16 and project radially outward therefrom. The length of the blades is sufficient to approximately equal the radius of the drill steel bottom bell 11. The leading edges of the blades 19 are inclined rearwardly to present a relatively sharp cutting edge.

The sizes and shapes of the shells are such that when together they will enclose the hexagonal drill steel 10 rather loosely so that the complete attachment may slide from end to end 20 of the drill steel. When drilling deep holes, exceeding ten feet in depth, the attachment is applied to the drill steel immediately above the bell 11 before the steel is inserted, since the dust ring 14 can be anticipated in deep holes.

25 The device is applied by simply placing the two shells 15 and 16 on opposite sides of the drill steel and forcing them together to align the sleeves 18. The pins 17 are then forced into place.

30 The improved dust ring removing attachment does not interfere in any way with the drilling operation and, when the drill steel is lifted and rotated, the sharpened blades 19 will rapidly scrape away the dust ring 14 to clear a passage for the bell 11 and the bit 12. The loosened dust from the ring will either be blown from the hole by the air discharge or will fall to the bottom of the hole.

In cases where the attachment was not applied 40 in advance and a drill steel has become stuck due to a dust ring, it can be applied to the steel above the hole with the blades 19 positioned on the bottom edge, and then allowed to slide down into the hole under the combined action of the vibration and rotation of the drill steel. As the attachment slides down the steel it will rapidly cut its way through the dust ring, allowing easy removal of the drill steel.

In Fig. 3 an alternate method of attaching 50 the device is illustrated. Two half shells 20 and 21 are employed, similar to the previously described shells 15 and 16. In this form, however, each shell is provided with a relatively thick, overlapping edge 22 which is notched to extend 55 over a relatively thin edge 23 on the opposite

section. The two edges 22 and 23 are then secured together by means of headless set screws 24. This form carries cutting blades 19 and operates exactly the same as the previously described form.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A dust ring removing attachment for a drill steel having a conventional drill bit comprising: two half shells shaped so that when together, they will surround the drill steel; interlocking pin sleeves along the adjacent edges of said shells; locking pins extending through said sleeves to lock said shells about a drill steel; and cutting blades projecting radially outward from said shells the radius of said blades being less than the radius of the drill bit. 15

2. A dust ring removing attachment for a drill steel having a conventional drill bit comprising: two half shells shaped so that when together, they will surround the drill steel, one extremity of each shell overlapping the adjacent extremity of the other shell; means for securing the overlapped extremities together; and cutting blades 30 projecting radially outward from said shells the radius of said blades being less than the radius of the drill bit.

3. A dust ring removing attachment for a hexagonal drill steel of the type having a drill bit 35 mounted on the extremity thereof comprising: a hexagonal shell slidably mounted on said steel, said shell rotating with said steel in consequence of the hexagonal shape of both; and cutting blades projecting equally and radially outward from one extremity of said shell at right angles 40

to the axis thereof the radial length of said blades being less than the radius of said drill bit so that said blades will engage and remove any dust ring which may tend to reduce the diameter of the hole drilled by said bit.

5. A dust ring removing attachment for a hexagonal drill steel as described in claim 3, in which the diameter of a circle described by the extremities of said blades when said shell is rotated is less than the diameter of the hole drilled by said drill bit.

10 6. The combination of a hexagonal drill steel; a drill bit of larger diameter than said steel mounted on the extremity of said steel and adapted to drill a hole about said steel; a removable hexagonal shell formed from two hinged together halves encircling said steel adjacent said bit, the coacting hexagonal shapes of the steel and shell causing said shell to rotate with said bit; means for locking the two hinged together halves together and cutting blades mounted on and extending radially outward from said shell into close proximity with the wall of the hole drilled by said steel to remove material adhering to said wall without increasing the diameter of said hole.

JOHN ALGER.
